GRAVITY PRESS

Albert Pohle, Brooklyn, N. Y.

Application April 24, 1937, Serial No. 138,741

6 Claims. (Cl. 101-3)

This invention relates to a gravity press.

The object of the invention is the production of a gravity press for embossing doilies, letterheads, leather goods, and various other articles.

5 The organization of the invention comprises a gravity press having a male and female die for objects to be embossed. The said objects are automatically positioned between the dies by clamping devices. The lower or male die is struck by a female die which drops at predetermined intervals. Clamping devices, by means of a conveyor locate the objects to be embossed between the dies at the proper times. The objects embossed are transferred to a conveyor which 10 positions them one after the other on a table board.

The essential object of the invention is the production of means for controlling the upper or female die of the press.

20 Other objects of the invention will appear from the description of the invention as set forth.

In the accompanying drawings Fig. 1 represents a side elevation of an exemplification of the improved gravity press; Fig. 1a shows an enlarged fragmentary portion of Fig. 1; Fig. 2 shows a top view of Fig. 1 with a portion in section; Fig. 2a indicates an enlarged partial section of Fig. 1 on the line 2a, 2a; Fig. 3 indicates a partial left hand view of Fig. 1; Fig. 4 is a section of Fig. 3 on the line 4, 4; Fig. 5 indicates an enlarged section of Fig. 1 on the line 5, 5; Fig. 6 shows a right hand view of some of the elements of Fig. 5; Fig. 6a shows portions of Fig. 6 on an enlarged scale; Fig. 7 represents a top view of Fig. 5; Fig. 8 indicates an enlarged partial section of Fig. 1 on the line 8, 8; Fig. 9 is a partial section of Fig. 8 on the line 9, 9 and Fig. 10 shows a side view of a clutch sleeve.

40 Referring to Figs. 1 to 4, the improved gravity press comprises a pair of side frames 20 and 25. Each of the side frames comprises the lower tapered portion 28, which joins with the upper rectangular upper portion 29. A central bridge 30 is fastened to the frames 20 and 25 at about the central portions thereof, and an upper bridge 31 is fastened to the top ends of said frames. At the lower ends of said frames are shown the feet 32, which later are supported upon and fastened to the base plate 35.

50 The main drive shaft 40 of the press has its ends journaled in the bearings 41 of the frames 20 and 25. A one revolution trip clutch mechanism, see Figs. 1, 2, 3, 8, 9 and 10, is indicated 55 to comprise a clutch sleeve loosely supported on

the shaft 40. The clutch sleeve comprises the portion 43 which has integral therewith the enlarged portion 44 having the heel 45. The portion 43 has a longitudinal opening 46. The shaft 40 is flattened for the wearing strip 48, which is 5 fastened to the shaft 40, by the screws 49. In the opening 46 is positioned the clutch roller 50. On the sleeve portion 43 is loosely supported the main drive gear 55. To the gear 55 are bolted four housings 56. In each of the housings is 10 slidably supported a plunger 57 having a shoe 58, at one end. A spring 59 bears against one end of the cavity 59a in the housing 56 and the shoe 58, to force the latter to the portion 44 of the sleeve. A groove 62 is indicated in the portion 15 44 of the clutch sleeve for the shoes 58. A collar 63 is fastened to the shaft 40 and bears against the portion 44 of the clutch sleeve, to maintain the clutch mechanism laterally in position.

A bearing 70, see Figs. 1 and 3, is integral with 20 the frame 25 and supports the stud 71 having the collar 72 at one end, and is clamped in place by the nut 73. A hub 75, is supported on the stud 71 between the frame 25 and the collar 72. From the hub 75 extends a bell crank comprising 25 the clutch dog 77 and the arm 78. A spring 79 has one end fastened to the frame 25 and its other end is fastened to the clutch dog 77.

On a rod 207, to be described, is supported the sleeve 80, which has integral therewith the journal bracket 81, and the latter supports a pin 82. A treadle 83 has one end fastened to the pin 82. An arm 84 has one end fastened to the pin 82. A link 85 has its ends pivoted to the arms 78 and 84.

35 When the operator bears on the treadle 83, the clutch dog 77 is released from the heel 45 of the portion 44 of the clutch sleeve. It is to be understood that the gear 55 continuously turns during the operation of the press. When the 40 clutch dog 77 has been released, the shoes 58 will cause the sleeve having the portion 44 to turn a little, and the clutch roller 50 is wedged between the wearing strip 48 and the hub of the gear 55, and thereby the shaft 40 is turned.

45 A worm gear housing 90 is supported on the base plate 35. An electric motor 91 is carried by the housing 90. A pinion of the worm gear housing is indicated at 93 and is in mesh with the gear 55.

50 With the rotations of the motor 91 the gear 55 is turned. On the main drive shaft 40 is fastened the gear 95 (see Figs. 1 and 3). A cam shaft 98 has its ends journaled in the frames 20 55

and 25 and has fastened thereto the gear 98 which is in mesh with the gear 95.

Referring to Figs. 1 and 3, a pair of cams 105 are fastened to the cam shaft 98. A pair of slide blocks 106 are loosely supported on the shaft 98. A pair of cam forks 107 each have a bifurcated member 108 and each cam fork has fastened thereto a lifting rod 109, by the screws 109a, as indicated. The lifting rods 109 are guided in the guide ways 110 of the frames 20 and 25. One of the rods 109 has integral therewith the lug 111. A cap 112 is bolted to each of the frames 20 and 25 over the guide ways 110, to maintain the lifting rods 109 in operative position.

15 To each of the cam forks 107 is journaled a roller 113 on the studs 114. The bifurcated members 108 straddle the slide blocks 106. On one end of the cam shaft 98 is fastened a V groove pulley 115. Adjacent to the gear 98 is fastened 20 to the cam shaft 98, a cam 116. The upper portion of each of the frames 20 and 25 has indicated therewith a pair of angle shaped guides 120, see Figs. 3 and 4. Four gibs 121 each having a V shaped groove 122, are positioned in the 25 angle shaped guides, 120. Two of said gibs 121 are clamped in position by the bolts 123, and the other two gibs 121 are held in position by the bolts 125, said bolts extending through the guides 120. The latter gibs are adjusted in place by the 30 bolts 127 with the jam nuts 128.

A slide is indicated in its entirety by the numeral 130, see Figs. 3 and 4. The slide 130 has integral therewith the cylindrical die head 132. At the lower end of the die head 132 is indicated the movable die holder 133 having the dovetail sides 134. A pair of clamping plates 135 are bolted to the front and rear portions of the die head 132 to detachably hold the die holder 133, in place. To the die holder 133 is fastened 40 the female die 136, by balls not shown. The die 136 can be placed in different angular positions. A male die 137 can be fastened in different angular positions to the die holder 138, having the dovetail sides 139. The holder 138 is slidably 45 supported above the central bridge 30. The said holder 138 is detachably locked in place by the clamping plates 135a, that extend from the bridge 30. A pair of wings 140 are integral with the slide 130. Each of the wings 140 has formed therewith a pair of V shaped grooves 142. A plurality of balls 144 are positioned between each of the grooves 142 and its adjacent groove 122. Plates 145 are bolted to the wings 140 to maintain the balls 144 in position. From each of the 50 wings 140 extends an adjusting bracket 148, and each of the latter carries an adjusting screw 150 with the jam nuts 151.

From the upper end of the die head 132 extends the cylindrical guide bar 153. At the upper 60 end of the guide bar 153 is fastened a stop plate 154 by means of the pin 155.

At the upper end of the guide bar 153 are shown a pair of adjusting nuts 156. A shock absorbing spring 157 is loosely supported on the 65 guide bar 153 and bears against the bridge 31.

In the guide bar 153, see Figs. 1, 1a and 3, is indicated the longitudinal keyway 158 for the key 159. The latter is fastened in place by the screws 160.

70 To the gibs 121 (see Fig. 4) are fastened a pair of journal brackets 162 which support a cross shaft 163. A bell crank 164 having the arms 165 and 166 is supported on the cross shaft 163. The said arm 166 is adapted to bear up against one 75 end of the key 159.

To a pair of the angle shaped guides 120 are bolted the journal brackets 168, which support the shaft 170. A stop collar 171 is fastened on one end of the latter shaft. On the other end of the shaft 170 is fastened the hub end 172 of the lever 173 having the forked end 174. To the middle of the shaft 170 is fastened an arm 175 and the latter is adapted to abut against the arm 168 of the bell crank 164. Adjusting rod 180 (see Figs. 1, 1a and 3) has its upper end 181 pivoted to the forked end 174 of the lever 173 and is guided in the lug 111 of one of the guide rods 109. On the lower end of the guide rod 109 are indicated a pair of adjusting nuts 181.

On top of the bridge 31 is supported a journal 18 bracket 190 having the leg 191, by means of the screws 192.

A shaft 194 is journaled in the bracket 190 and at the central portion of the shaft 194 is fastened the cam 195. At one end of the shaft 194 is fastened the hub end of a handle 196.

At the upper end of the bracket 190 is journaled a second shaft 197. On the shaft 197 is loosely supported a bell crank having the arms 198 and 199. To one end of the arm 198 is connected one end of the spring 200. The other end of the spring 200 is connected to the leg 191.

The operation of the die head 132 is as follows.

When the clutch mechanism for the main driving shaft 40 is engaged therewith, the said shaft turns. Thereby the gears 95 and 98 are turned. The cam shaft 98 turns with the gear 98 and the said cam shaft 98 makes one revolution for every revolution of the clutch mechanism. The cams 105 of the shaft 98 raise the cam forks 107. The lifting rods 109 rise with the forks 107. The lifting rods 109 abutting against the screws 150, cause the die head 132 to rise. When the cams 105 raise the die head 132 to the end of its up stroke, the arm 166 of the bell crank 164 locks with the key 159. At this instant the die head 132 is held in locked position at the upper end of its stroke. The lifting rods 109 now return to their lower position. At the end of the down stroke of the rods 109 the lug 111 will contact with the adjusting nuts 181 of the adjusting rod 180. The said rod 180 swings down the lever 173 and the arm 175 will contact with the bell crank arm 165, which disengages the bell crank arm 166 from the key 159. By this means the die head 132 with the die drops by gravity and coacting with the lower die described embosses the object operated upon.

When the female upper die drops to the end of its stroke, the tension of the spring 157 cushions the force of its descent and provides means for the rebounding of the female or upper die.

For the operator of the press to locate the dies in place, or make adjustments, a safety device is provided to avoid injury by the descent of the die head 132.

When the operator swings the handle 196 in the direction of the arrow M Fig. 1, the cam 195 releases the arm 199 from the stop plate 154, by means of which the die head 132 can descend. 65 When the handle 196 is in the position indicated (see Fig. 1) the die head 132 cannot descend.

The spring 157 as shown in Fig. 1 acts as a cushion for the die head 132 and the location of the nuts 156 controls the force when the die head 70 is at the end of its down stroke.

To the base plate 35 are fastened pairs of brackets 206. The said brackets 206 support each one end of a rod 207. Stands 208 have extending therefrom the vertical supporting rods 210 and 75

211. Each of the latter rods supports a bracket 212. The latter each support one end of the rods 207. On the supporting rods 210 are secured the journal and supporting brackets 215. At the upper end of each supporting rod 211 is fastened a journal and supporting bracket 218 at the rear or exit end of the apparatus. From the bars 246 to be described extends the curved guide plate 218a. With each of the brackets 218 is indicated 10 the lug 219. On each of the rods 211 is supported the triangular shaped bracket 220 with the inclined table board 222.

The latter has adjustably connected thereto the stop angle plate 225.

15 An adjusting screw 230 is carried by each of the brackets 219. At one end of each of the screws 230 is supported an open journal bracket 231. A shaft 232 with the roller 233 is supported in the journal brackets 231. At the upper ends 20 of the brackets 218 is journaled a conveyor drive chain shaft 235. To the shaft 235 are fastened the large sprocket chain wheels 238 and the small sprocket chain wheel 239. In the supporting brackets 215 is journaled a conveyor chain shaft 25 241. The latter has fastened thereto the large sprocket chain wheels 244. Pairs of supporting bars are indicated at 246 which are supported at their outer ends by the brackets 215 and 218, and at their inner ends by the bridge 30, and have connected thereto the crossbars 247.

30 A feed table 250 is supported on the supporting bars 246.

A pair of conveyor sprocket chains are each indicated at 252 and are supported upon the sprocket chain wheels 238 and 244. Each of the chains 252 carries a plurality of pins 253 (see Fig. 5) and on each of said pins is journaled a guide roller 254. A pair of guide rails 256, each having the U shaped groove 257, have integral therewith the legs 258. The latter are supported upon and fastened to the cross bars 247.

The guide rollers 254 engage the U shaped grooves 257. The rails 256 have extending therefrom the legs 259.

45 The members 261 and 262 of a table are supported on the bars 246 and the lugs 259. To the connecting bars 247 are fastened a plurality of brackets 265, one of which is shown in Fig. 5. The brackets 265 support the central member 50 266, of said table. To each of the chains 252 are connected a plurality of clamping devices, each 55 designated in its entirety by the numeral 270, (see Figs. 1, 2, 3, 5, 6 and 7). Each clamping device 270 comprises a pair of lugs 271 and each of the latter is supported on a pair of the pins of its sprocket chains 252.

To each pair of the lugs 271 is pivoted an angle shaped clamping bar 273, by means of the screw pivot 273a. Integral with each clamping bar 273

60 is indicated a journal bracket 274. In each pair of the journal brackets 274 is journaled a shaft 275. To the shaft 275 is fastened a clamping lever, comprising a pair of arms 276 with the connecting member 277. A rubber pad 278 is fastened to the lower face of the member 277. A 65 tapered operating arm 280 for each clamping device 270 is integral with one of each pair of arms 276. At one end of the shaft 275 is supported the helical spring 282. One end of the spring 282 is 70 fastened to one of the journal brackets 274 and its other end is fastened to a tension collar 283, the latter being fastened to the shaft 275.

On one of the bars 246 (see Fig. 1) is fastened 75 a journal bracket 288, and to the bridge 30 is fastened a journal bracket 289. A rack shaft

290 has its ends journaled in the brackets 288 and 289. A lever 293 having the forked end 294 has its hub end fastened to the shaft 290. A connecting rod 295 connects the forked end 294 of the lever 293 and the treadle 83. A controlling arm 296 is 5 fastened to one end of the shaft 290 and coacts with the operating arm 280. A bell crank, (see Fig. 1), 297 having the arms 298 and 299, is pivoted to the frame 20, by means of the pivot 300. To the arm 299 is journaled a roller 302 which 10 coacts with the cam 118. The arm 298 has a forked end 303, which carries a pin 304. The pin 304 supports the rod 306, having a thread at one end for the clamping nuts 307 and 308, which bear 15 against the pin 304.

The other end of the rod 306 has an eye end 309. A journal bracket 310 and a journal bracket 311 are fastened to the bridge 30. The bracket 310 has integral therewith the journal bearing 310a and has extending therefrom the pin 312. 20 The bracket 311 has integral therewith the rack guide 313, and journal bearing 315. A vertically sliding rack bar 316 is guided in the rack guide 313 and is shown with the forked member 317 at its lower end. The latter is pivoted to the 25 connecting rod 306, by means of the pin 319. In the journal brackets 310 and 311 is journaled a cross shaft 321. A gear 322 is loosely supported on the shaft 321 and is in mesh with the 30 teeth of the sliding rack bar 316.

To the gear 322 is fastened the ratchet wheel 323 having a pair of teeth. On the shaft 321 is fastened a disc 327 which carries a pawl 328. The latter coacts with the teeth of the ratchet wheel 323. To the central portion of shaft 321 35 is fastened a sprocket chain wheel 330. A sprocket chain 332 engages the sprocket chain wheels 330 and 239.

In the journal bearings 310a and 315 is supported a shaft 335. A belt pulley 336 is fastened 40 to the central portion of the shaft 335. To one end of the shaft 335 is fastened a pulley 338 having the V groove 339. A V shaped belt 340 connects the pulley 338 and the pulley 115. A belt 342 connects the pulley 336 and the pulley 233. 45

On the table 250 are placed a plurality of doilies 345 or other objects to be embossed.

When the press stops the operating arm 280 contacts with the lever 296, and thereby the arm 277, which is normally in the closed position, is 50 swung open. The operator now places one or more doilies between the clamping bar 271 and the rubber pad 278 (see Figs. 6 and 7). The operator now bears on the treadle 83, and the connecting rod 295 pulls down the lever 293 and 55 thereby the shaft 290 is slightly turned. At the same time the arm 296 moves to permit movement of the member 277 of the clamping device.

The clamping device 270 grips one or more of 60 the doilies 345 and moves them in position between the centers of the dies 136 and 137.

The sprocket chains 252 are moved as follows. The cam 118 swings the bell crank 297, and the arms 298 pull down, by means of the rod 306, 65 the rack bar 316. The latter turns the gear 322 and thereby the pawl 328 turns the disc 327 with the cross shaft 321. With the rotations of the shaft 321 the sprocket chain wheel 330 is turned, which moves the sprocket chain 332 70 and the conveyor chain shaft 235 is turned by the sprocket chain wheels 239. The rotations of the sprocket chain wheels 239 turn the shaft 235. The wheels 238 turn with the shaft 235 to 75 drive the chains 252.

Each time the operator trips the foot treadle 83, the chains 252 move in the direction of the arrow A, Fig. 1, and the dollies 345 are carried around the sprocket wheels 238, within the guide plate 218a and move with the chains 252 until the operating arm 288 strikes the pin 312 and the members of the clamping device 270 are opened.

The dollies now drop to the belt 342 and are conveyed in the direction of the arrow B, Fig. 1 to the table board 223, on which they are deposited for removal. The stop angle plate 225, can be adjusted in various positions for dollies of different sizes.

15 Attention is called to the fact that the members of the clamping device having the arms 276 can be moved forward or to the rear by locating the sprocket chain wheels 238 in different angular positions on the shaft 235, to cause the chains 252 to locate the clamping device having the arms 276 with the dollies in proper position.

The operating arm 296 is also adjustable to open the members of the clamping device 270, when the chain 252 is stopped between the dies 25 136 and 137.

Various modifications might be made in the invention and the present exemplification is to be taken as illustrative and not limitative thereof.

30 Having described my invention I claim:

1. In an apparatus of the character described the combination of a pair of frames, gib supported on the frames, each of said gibs having a V shaped groove, a slide in the apparatus, said 35 slide being V shaped grooves positioned opposite the V shaped grooves in the gibs, a plurality of balls in the V shaped grooves of the slide and its coating V shaped groove in its adjacent gib and plates at the top and bottom ends of the 40 slide for each plurality of balls.

2. In an apparatus of the character described the combination of a pair of frames, an upper bridge connecting the upper ends of the frames, a reciprocating slide supported in the frames, a 45 die head carried by the slide, a female die carried by the die head, a guide bar extending from the slide and actuated thereby, said guide bar extending through said bridge, a shock absorbing spring encircling the guide bar and bearing 50 on said bridge, a pair of adjusting nuts on the guide contacting with said spring upon the descent of the die head, a central bridge connecting said frames, a die holder supported on the central bridge, a male die carried by said die holder, said 55 adjusting nuts with the descent of the die head contacting with said spring and cushioning the blow of the female die and rebounding the same.

3. In a press of the character described the combination of a pair of frames, a cam shaft 60 journaled in the frames, means to rotate the cam shaft, cams supported on the cam shaft, a pair of cam forks in the press, a roller journaled to each cam fork coating with said cams to move the cam forks, a lifting rod connected to 65 the upper end of each cam fork, a slide guided in the press, a die at the lower end of the

slide, brackets extending from the slide, and an adjusting screw supported in each bracket coating with said lifting rods to raise the slide with the rotation of the cam shaft.

4. In a press of the character described the combination of a pair of frames, a lifting rod adjacent to each frame, a slide guided in the frames, a die head carried by the slide, a guide bar extending from the die head, means to lift the lifting rods, a lug integral with one of the lifting rods, an adjusting rod guided in said lug, a pair of adjusting nuts at the lower end of the adjusting rod, a shaft journaled at the upper portions of said frames, an arm and a lever extending from said shaft, the swinging end of the lever pivoted to the adjusting rod, a second shaft journaled at the upper portions of the frames, a bell crank fastened to the latter shaft, and means on the guide bar adapted to be locked with an arm of said bell crank, the lifting rod having the 20 lug when descending engaging the said adjusting nuts and thereby causing the lever extending from said first shaft to swing down and thereby forcing the arm of the latter shaft against one of the arms of the bell crank and thereby disengaging the other arm of the bell crank from the 25 guide rod.

5. In a press of the character described the combination of a pair of frames, a lifting rod adjacent to each frame, a slide guided in the frames, 30 a die head carried by the slide, a guide bar extending from the die head, means to raise the lifting rods, means between the lifting rods and slide to raise the latter with the up stroke of the lifting rods, a lug integral with one of the lifting 35 rods, an adjusting rod guided in said lug, a pair of adjusting nuts at the lower end of the adjusting rod, a shaft journaled at the upper portions of said frames, an arm and a lever extending from said shaft, the swinging end of the lever 40 pivoted to the adjusting rod, a pair of journal bearings extending from the upper portions of the frames, a shaft journaled in the latter bearings and a bell crank fastened to the latter shaft, a key extending from the guide bar adapted to 45 be locked with one of the arms of the bell crank, the lifting rod having the lug, when descending engaging the adjusting nuts of its adjusting rod, pulling down the lever extending from the first of said shafts and thereby forcing the arm of said 50 latter shaft against one of the arms of the bell to disengage the other arm of the bell from the key of the guide rod and thereby releasing the slide of the press with its die head.

6. In an apparatus of the character described 55 the combination of a pair of frames, a bridge connecting the upper ends of the frame, a reciprocating slide guided in the frames, a die head carried by the slide, a die carried by the die head, a guide bar extending up from the die head, 60 said guide bar extending through said bridge, a spring encircling the guide bar and bearing on said bridge and a pair of adjusting nuts on the guide bar adapted to contact with said spring upon the descent of the die head.

ALBERT POHLE. 65
